UNITED STATES PATENT OFFICE.

OSCAR V. PAYNE, OF CLEVELAND, OHIO, ASSIGNOR TO AUTO-ORDNANCE CORPORATION, OF NEW YORK, N. Y., A CORPORATION OF NEW YORK.

CARTRIDGE-MAGAZINE.

1,350,619.

Specification of Letters Patent. Patented Aug. 24, 1920.

Application filed May 15, 1919. Serial No. 297,286.

To all whom it may concern:

Be it known that I, OSCAR V. PAYNE, a citizen of the United States of America, and resident of Cleveland, in the county of Cuyahoga and State of Ohio, have invented new and useful Improvements in Cartridge-Magazines, of which the following is a specification.

This invention relates to cartridge magazines and more particularly to the flat elongate type adapted to hold cartridges transversely therein, either in a single column or in a double column with the cartridges of the two columns disposed in staggered relationship with each other, and adapted to be detachably secured to firearms in position to feed the cartridges thereto.

The principal objects of the invention are to provide a magazine which is simple and reliable in construction, which is light in weight so that it does not appreciably add to the weight of a firearm when attached thereto, which is inexpensive to produce—even to the extent that it may be discarded when emptied, which may be formed entirely of sheet metal, which has a guide pressed therein for detachably connecting it to a firearm, which may be assembled and disassembled without tools, which has a follower adapted to lift the rearmost cartridge of each column of two staggered columns of cartridges, and which has means for controlling the action of an automatic gun when the magazine becomes empty.

In one aspect the invention comprises a cartridge case, preferably a sheet metal case of tubular form, having a wall bent to form a guide adapted to fit into a corresponding guide in a firearm, said wall preferably being pressed outwardly to form a hollow guide having a T-shaped cross-section, whereby the case may be detachably fitted to a firearm. More specifically the invention comprises a tubular case having a longitudinal slot in one side thereof and having a hollow guide disposed longitudinally along said side, said guide having a T-shaped cross-section and having its edges integrally connected to the edges of said slot the base of said T-shaped guide being relatively wide so as to have overhanging portions adapted to fit into the recesses of a recessed channel in a firearm or other device to which it is desired to attach the magazine.

In another aspect the invention consists in

a magazine having a delivery opening through which cartridges may be delivered to a firearm or the like, and means including a follower for impelling cartridges toward said opening, together with means associated with the follower for stopping or otherwise controlling the action of the firearm. When the magazine comprises a tubular case of the type herein described, having a hollow guide along one side, the means on the follower for controlling the action of the firearm preferably extends into said hollow guide so as to engage a part of the control mechanism of the firearm when the magazine becomes either wholly or partially empty. In order to receive the said part of the control mechanism of the firearm a portion of said guide is cut away and preferably the upper end of the guide is cut away so that the guide terminates at a distance from the delivery end of the magazine sufficient to permit said means associated with the follower to project beyond the end of the guide when the magazine becomes empty.

In another aspect the invention comprises a closure for the rearward end of the tubular cartridge case having at least one portion extending along the wall of the case and thence into a slot or other opening in the wall of the case and preferably two such portions on opposite sides thereof adapted to extend into slots in the opposite sides of the tubular case. The closure is preferably formed of sheet metal and when so formed said portions are preferably in the form of integral tabs or fingers bent at right angles to the closure and adapted to extend along the inside of the walls of the case and to hook into said slots, said tabs or fingers being sufficiently flexible to be unhooked from said slots by forcing them inwardly.

In still another aspect the invention comprises a unique follower having a transverse portion adapted to engage the cartridges and having longitudinal portions extending from opposite sides of said transverse portions along opposite walls of the case to hold the follower in proper position. The follower is preferably formed of sheet metal and when so formed said longitudinal portions are preferably in the form of right-angle flanges adapted to slide along opposite walls of the case. A portion of one of these flanges may be struck up to form the aforesaid control means adapted

to extend into said hollow guide. When the magazine is made of such width as to hold cartridges in two columns with the cartridges of the two columns disposed in staggered relationship to each other, the follower is shaped to engage the rearmost cartridge of each column by providing a raised portion on one side thereof. When the follower is formed of sheet metal said raised portion is preferably formed by bending one side of the follower upwardly as hereinafter described.

In order more clearly to set forth the nature of my invention I have illustrated the 15 preferred embodiment thereof in the accompanying drawings, in which—

Figure 1 is a front elevation of the magazine, the lower portion being broken away;

Fig. 2 is a side elevation, the lower portion being broken away;

Fig. 3 is a rear elevation, the lower portion being broken away;

Fig. 4 is a vertical transverse section of the magazine looking rearwardly, showing 25 the parts in the position which they occupy when a bolt is above the magazine;

Fig. 5 is a vertical transverse section looking forwardly, showing the parts in the position which they occupy when the bolt is 30 retracted from above the magazine;

Fig. 6 is a top plan view of the magazine;

Fig. 7 is a perspective view of the bottom closure;

Fig. 8 is a perspective view of the follower;

Fig. 9 is a sectional view of the magazine applied to one type of firearm;

Fig. 10 is a side elevation of a portion of the firearm shown in Fig. 8; and

Fig. 11 is a section on line 11—11 of Fig. 10.

The particular embodiment of the invention shown for the purpose of illustration comprises an elongate tubular case C having a cross-sectional contour which in general is rectangular as shown in Fig. 6. The forward wall of the case is cut away at the upper end as shown at 1 in Fig. 1 to permit cartridges to be fed outwardly from the forward side of the magazine. The side walls of the case are bent inwardly at the upper end as shown at 2 and 3 to form stops adapted to prevent the cartridges from being forced outwardly through the upper open end of the case. Sight openings O are provided at intervals along the right-hand side of the case to show approximately how many cartridges are contained in the casing at any time. The rear wall of the case is provided with a longitudinal slot 4 which extends throughout the entire length of the case. A T-shaped guide 5 is provided along the rear side of the case for the purpose of detachably securing the magazine to a firearm or the like, this guide

being adapted to slide into a similarly shaped guide in the firearm or other device. The base of the T-shaped guide is made wider than the portion 6 disposed between the base and the case so as to form 70 flanges 7 and 8 adapted to fit into the recesses of a recessed guide channel. The guide 5 is integrally connected to the edges of the slot 4 and is preferably formed by pressing the rear wall of the case outwardly, the case being formed of pressed metal. The upper portion of the guide 5 is cut away so that the guide terminates at the plane 9 as shown in Fig. 3. The guide is provided with an opening 10 to receive a 80 catch on the firearm to hold the magazine in position.

The lower end of the tubular case is closed by means of the closure shown in perspective in Fig. 7. This closure 85 comprises a bottom portion 11 adapted to fit snugly into the cartridge case and a T-shaped projection 12 adapted to close the lower end of the guide 5. On opposite sides of the bottom closure are integral tabs 13 90 and 14 which bend upwardly at right angles and at their upper ends these tabs are bent outwardly so as to hook into slots 15 and 16 in the opposite walls of the cartridge case. The upper ends of the tabs 13 and 14 are 95 bent outwardly only a sufficient distance to project into the slots in the cartridge case and not far enough to project outwardly from the case when positioned in the slots. The bottom closure may be removed by 100 pressing inwardly on the bent ends of the tabs 13 and 14 which are disposed in the slots 15 and 16 until they are unhooked from the slots. The bottom closure is preferably formed of a single piece of sheet 10 metal stamped and pressed into the form shown in Fig. 7.

A follower F is provided to engage the rearmost cartridges in the magazine as shown in Figs. 4 and 5 and interposed between the follower F and the bottom closure 11 is a coiled compression spring 17. The follower F is provided with a transverse portion 18 and with longitudinal portions 19 and 20. The follower is formed of sheet 11 material and the longitudinal portions 19 and 20 are bent downwardly at right-angles to form flanges adapted to slide along the forward and rearward walls of the magazine case. In order to engage the rearmost 12 cartridges of each column of cartridges, as illustrated in Figs. 4 and 5, a raised portion 21 is formed on one side of the follower by providing a lateral extension on one side of the transverse portion 18 and bending extension into the form shown in Figs. 4 and 5, preferably by a stamping operation. As illustrated in Figs. 4 and 5 the final form of this raised portion comprises a 180° bend or fold at 22, and 90° bends at 23, 24 and 130

25, the height of the raised portion being such that the raised portion engages the lowermost cartridge of one column when the lowermost cartridge of the other column 5 rests on the transverse portion 18. In this way the impelling force of the follower is applied substantially equally to each column of cartridges, thereby avoiding any tendency for the cartridges to wedge or bind. A tab 10 26 is struck up from the flange 20 so as to extend outwardly through the slot 4 into the guide 5, the tab 26 being so positioned on the follower that it extends above the upper end of the guide when the magazine is 15 empty as shown in Fig. 3.

In Figs. 9 and 10 I have shown the magazine applied to a firearm of the type disclosed in my prior application, Serial No. 282,642, filed March 14, 1919 and also in my 20 applications Serial Nos. 297,282, 297,283, 297,284 and 297,285 filed on even date herewith. This firearm is provided with a frame 27 which has a channel 28 in its forward face adapted to receive the guide 5 of the 25 magazine, the guide 5 sliding upwardly into this channel from the bottom. The firearm is provided with a catch 29 adapted to hook into the opening 10 in the magazine guide and hold the magazine in the position shown 30 in Fig. 9. In this particular firearm the catch 29 comprises a part of a lever 30 which is pivotally mounted on the left-hand side of the frame 27 by means of a circular lug 31 projecting inwardly from the inner 35 side of the arm into a circular opening in the frame 27. This construction is described and claimed in my aforesaid application, Serial No. 297,282 and in so far as the present invention is concerned it is sufficient 40 merely to state that the arm 31 is normally urged in a clockwise direction by means of a coil spring surrounding the lug 31 so as to hold the catch 29 in the position shown in Fig. 9 and that in order to remove the magazine 45 the arm 30 is shifted in a counter-clockwise direction until the catch 29 disengages the magazine guide.

The breech action, which is described in my aforesaid application Serial No. 282,642, 50 comprises a bolt which has a large rearward portion 32 arranged to reciprocate to and fro in the receiver R behind the region of the magazine and a smaller forward portion 33 adapted to move to and fro above 55 the magazine. As described in my prior application the action of the bolt is automatic and each time the bolt moves forwardly it forces a cartridge out of the magazine and carries it forward into the firing 60 chamber. While the portion 32 of the bolt is above the magazine the lower side of the bolt extends into the magazine so as to prevent the foremost cartridge from being advanced by the follower to the uppermost position shown in Fig. 5. After the portion

32 of the bolt has been retracted to the position shown in Fig. 9 in the rear of the magazine the foremost cartridge moves up into the position shown in Fig. 5 so that its upper portion is disposed in the path of the bolt. 70 When the bolt moves forwardly the cartridge is pushed out through the delivery opening 1 of the magazine and this action is continued until the magazine becomes empty. 75

The mechanism for controlling the breech action, which is described and claimed in my aforesaid application Serial No. 297,282, comprises a sear 33 pivotally mounted at 34, a trigger 35 pivotally mounted at 36, a dis- 80 connector 37 disposed between the trigger 35 and the sear 33, and a yoke 38 surrounding the upper portion of the trigger and pivoting on the same shaft 36. A spring normally urges the sear into engagement 85 with the bolt and a spring 40 urges the disconnector 37 into the position wherein the projection 41 will engage the sear when the trigger is pulled to disengage the sear from the bolt. The yoke 38 is provided with an 90 extension 42 which extends into a position above the guide 5 of the magazine where it is engaged by the tab 26 on the follower when the magazine is empty. When the tab 26 engages the end 42 of the yoke the 95 yoke is rotated in a clockwise direction into the position shown in Fig. 9 wherein it rotates the disconnector 37 in a counter-clockwise direction against the action of the spring 40 until the projection 41 of the dis- 100 connector is brought into such position that it will not engage the sear when the trigger is pulled. Consequently when the magazine becomes empty the parts are automatically moved into the position shown in Fig. 9 105 wherein the bolt is held in retracted position even though the trigger be pulled, until the magazine is detached from the firearm. 110

In assembling my improved magazine the follower is first inserted through the open bottom of the cartridge case, the spring is placed in position and the bottom closure is then inserted into the position wherein the fingers 13 and 14 hook into the slots 15 and 115 16. To attach the magazine to the firearm it is merely necessary to slide the guide upwardly into the channel guide in the frame 27, the catch 29 being automatically retracted due to the fact that its forward end 120 is beveled. To disconnect the magazine from the firearm it is necessary merely to shift the lever 21 in a counter-clockwise direction until the catch 29 disengages the magazine whereupon the magazine will 125 either slide out by gravity or may be manually detached.

What I claim is:

1. A cartridge magazine adapted to be detachably fitted to a firearm, comprising 130

a sheet metal case having a wall thereof bent outwardly in the form of a dove-tail guide adapted to fit into a similarly shaped channel in the firearm.

2. A cartridge magazine adapted to be detachably fitted to a firearm comprising a tubular case having a wall thereof flared outwardly to form a guide adapted to fit into a channel in the firearm, said guide 10 having a relatively wide portion and having a narrower portion between the wide portion and the case.

3. A cartridge magazine adapted to be detachably fitted to a firearm comprising a 15 tubular case having a longitudinal portion of its wall pressed outwardly in the form of a T-shaped guide adapted to fit into a similarly shaped channel in the firearm.

4. A cartridge magazine comprising a 20 tubular case having a longitudinal slot in one side thereof, and a hollow guide disposed longitudinally along said side of the case for detachably fitting the magazine to a firearm, said guide having a T-shaped cross-section and having its edges integrally connected to the edges of said slot.

5. A cartridge magazine comprising a 25 tubular case having a longitudinal slot in one side thereof, and a hollow guide disposed longitudinally along said side of the case for detachably fitting the magazine to a firearm, said guide having a T-shaped cross-section and having its edges integrally connected to the edges of said slot, the base 30 of said T-shaped section being relatively wide so as to form overhanging portions adapted to fit into the recesses of a recessed channel.

6. A cartridge magazine adapted to be 40 detachably fitted to a firearm comprising a tubular case having a delivery opening at one end and having a longitudinal portion of its wall pressed outwardly in the form of a hollow guide adapted to fit into a channel in the firearm, and means including a 45 follower for impelling cartridges toward said opening, said follower having a portion projecting into said hollow guide.

7. A cartridge magazine adapted to be 50 detachably fitted to a firearm comprising a tubular case having a delivery opening at one end and having a longitudinal portion of its wall pressed outwardly in the form of a hollow guide adapted to fit into a channel in the firearm, and means including a 55 follower for impelling cartridges toward said opening, said follower having a portion

projecting into said hollow guide, said portion being arranged to control the action of the firearm when the magazine becomes 60 empty.

8. A cartridge magazine comprising a tubular case having a longitudinal slot in one side thereof, and a hollow guide disposed longitudinally along said side of the 65 case for detachably fitting the magazine to a firearm, said guide having a T-shaped cross-section and having its edges integrally connected to the edges of said slot, and a spring-actuated follower in said case for 70 impelling cartridges toward the delivery opening of the magazine, said follower having a portion projecting into said hollow guide, and said guide being cut away in the region occupied by said portion of the follower when the magazine is empty.

9. A cartridge magazine comprising a tubular case having a longitudinal slot in one side thereof, and a hollow guide disposed 75 longitudinally along said side of the case for detachably fitting the magazine to a firearm, said guide having a T-shaped cross-section and having its edges integrally connected to the edges of said slot, and a spring-actuated follower in said case for 80 impelling cartridges toward the delivery opening of the magazine, said follower having a portion projecting into said hollow guide, and said guide terminating at a distance from the delivery end of the magazine such that said 85 portion of the follower extends beyond the end of the guide when the magazine is empty.

10. A cartridge magazine comprising an elongate case having a delivery opening 95 therein, and means including a sheet metal follower for impelling cartridges toward said opening, said follower having a transverse portion adapted to engage the cartridges and having end portions bent at 100 right angles along opposite sides of the case, one of said end portions having a struck-up tab extending outwardly into a longitudinal opening in the case.

11. A cartridge magazine adapted to be 105 detachably fitted to a firearm, comprising a sheet metal case having a wall thereof bent in the form of a dovetail guide adapted to interfit with a similarly shaped guide in the firearm.

Signed by me at Cleveland, Ohio, this 110 18th day of April, 1919.

OSCAR V. PAYNE.
